United States Patent Office

Des. 203,639
Patented Feb. 1, 1966

203,639

REFRACTORY BLOCK

Charles H. Miller, 6639 Harrington, Youngstown, Ohio,
and William J. Wilson, 156 Northwest St., Columbiana,
Ohio

Filed Mar. 11, 1965, Ser. No. 84,215

Term of patent 14 years

(Cl. D81—25)

FIG. 1

FIG. 2

FIG. 3

FIGURE 1 is a perspective view of a refractory block showing our new design;

FIGURE 2 is a plan view thereof; and

FIGURE 3 is a partial sectional elevational view taken along the line 3—3 of FIGURE 2.

We claim:

The ornamental design for a refractory block, substantially as shown.
